UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed July 6, 1920. Serial No. 394,091.

- This invention relates to fastening inserting machines of the type designed to handle previously formed fastenings and known as "loose nailing machines." 5
- Such nailing machines usually comprise a nail receiver in the form of a throat constructed to provide a nail receiving passage, a slotted raceway arranged to conduct nails from a suitable source of supply to a point adjacent to the nail receiver, a separator operating to deliver nails one at a time from the raceway to the passage of the nail receiver, a driver, and an awl for feeding the work between successive nail inserting operations of the driver. Machines of this type have been devised which will operate efficiently on nails having heads of ordinary size, but great difficulties are encountered in the use of such machines on nails having heads of large size, particularly when the heads of the nails are angular in transverse section and non-uniform in shape and size as in the case of certain species of nails, commonly called "hob-nails." 15
- Objects of this invention are to provide a machine which will operate more efficiently on large-headed nails than will known machines, and which will also successfully handle nails, such as hob-nails, whose heads are not only of large size but are also angular in transverse section and irregular in shape and size. So far as applicant is aware, nails of the character last described have, heretofore, always been inserted by hand. 20
- With a view to the attainment of these and other objects which will appear as the description proceeds, important features of the invention reside in improved means for delivering fastenings from a raceway and presenting them in position to be operated upon, for example, by means for inserting them into a piece of work. In the illustrated machine, the endmost fastening in the raceway, while enclosed by a fastening receiver, is isolated from the remaining fastenings by a separator of novel construction and operation and is then moved to the line of drive of the fastenings by movement of the separator and the fastening receiver together substantially in line with the fastenings in the raceway. As shown, the fastening receiver is constructed to provide a chamber open at one side, and the separator when it is advanced to isolate the endmost fastening in the raceway is disposed across the open side of the receiver and co-acts with it to constitute a substantially closed chamber about the fastening, the construction and arrangement of the parts being such that the fastenings are withdrawn from the raceway under uniform conditions which preclude the escape of any of them from the machine and cause them to be properly disposed for the action of the driver. 60
- Other features of the invention pertain to the provision of a fastening receiver mounted for to and fro movement between the line of drive of the fastenings and the means for delivering fastenings to the receiver and a work feeding awl having its carrier mounted on the frame of the machine for movement independently of the receiver. In the illustrated machine the receiver is carried by a head mounted to swing in a plane substantially parallel to the direction of movement of the awl carrier, and the awl carrier is operated by mechanism distinct from the mechanism for operating the head but comprising an actuating element common to itself and the head operating mechanism. An important advantage arising from the provision of operating means for the awl carrier distinct from the means for operating the head is that the work feeding movement of the awl may be varied as desired without affecting the range of to and fro movement of the head. Preferably, and in the illustrated embodiment of the invention, the means for varying the work feeding movement of the awl is so constructed that in all positions of adjustment of such means, the awl terminates its work feeding movement in the line of drive of the fastenings. 70
- The invention further aims to provide improved means associated with the fastening receiver for insuring that the fastenings will be driven straight into the work. 80
- Although the illustrated machine will hereinafter be described with special reference to its use for inserting large-headed nails, it is recognized that the invention is not restricted in its application to such nails, but is capable of being usefully employed in other ways, including employment for inserting nails of usual form. Accordingly, 90 the scope of the invention is not intended to be limited except as required by the claims. 100
- Other objects and features of the invention will appear as the description proceeds and will be pointed out in the appended claims. 110

Fig. 14 is a section through the center of the nail receiver;

Fig. 15 is a view of one of the combined throat and nail guide members;

Fig. 16 is a view of the separator; and

Fig. 17 is a view in elevation and partly in section of the lower end of the raceway and the nail receiver.

The illustrated machine comprises a column 2 carrying a superstructure 4 on which the operating instrumentalities of the machine are mounted. The operating instrumentalities include a rotary hopper 6 constructed with internal flanges 7 and constituting a source of supply of nails in bulk, from which the nails are delivered to a raceway 8 stationarily supported on a frame member 10 rigidly bolted at 11 to the superstructure 4. The frame member 10 also supports the rotary hopper 6. The raceway 8 has connected therewith a plate 12 having an opening in its end nearest to the lower, delivery end of the raceway to receive an eccentric 14 on a stud bolt 16 extending forwardly from the frame member 10. The stud bolt 16 passes through a slot 18 in the plate 12 disposed to permit endwise adjustment of the raceway. The slot 18 is made of a width greater than the diameter of the bolt 16 to enable the delivery end of the race-

way to be adjusted vertically. At its other end, the plate 12 is formed with an open-ended slot 20 through which passes a stud bolt 22. The slot 20 is so disposed as to allow the raceway 8 to be adjusted endwise, and the bolt 22 affords a fulcrum point for the plate 12 and raceway 8 when the delivery end of the raceway is adjusted vertically. The plate 12 and raceway 8 may be secured firmly in any position in which they may be set by tightening the bolts 16 and 22. As shown, the raceway 8 comprises outer and inner bars 23, 24 (Figs. 9 and 10) clamped to each other and the plate 12 by bolts 25 (Fig. 2) and channeled horizontally adjacent to their lower ends to receive detachable plates 26 having curved upper surfaces constituting an elongation of the upper edge of the raceway and converging toward their lower surfaces beyond the bars 23 and 24 to form comparatively narrow tips on the delivery end of the raceway. As shown, the plates 26 are secured to the bars 23 and 24 by screws 27.

Rotation is imparted to the hopper 6 by a flanged gear 28 on the hopper with which meshes a gear 29 on a shaft 30 rotatably mounted in bearings 31 and 32 on the frame member 10. Loosely journaled on the shaft 30 is a pulley 34 operatively connected by a belt 36 with a loose pulley 38 on the main shaft 40 which, in turn, is supported by suitable bearings in the superstructure 4. Keyed to slide on the shaft 30 within the bearing 32 is a sleeve 42 provided on one of its ends with a cone positioned for clutching engagement with the loose pulley 34 and normally urged into contact with the pulley 34 by a spring 44 coiled about the shaft 30 between a collar 46 fast on the shaft and a flange 48 on the adjacent end of the sleeve 42. Fulcrumed on the bearing 32 is a forked bell crank lever 50 having short arms 51 arranged to act on the flange 48 and a long arm 52 joined to a rod 54 mounted to slide on the frame member 10 and having a finger piece 56 on its forward end positioned near the front of the machine so that it may be readily grasped and manipulated by the operator. When the rod 54 is drawn forwardly, the sleeve 42 is moved out of clutching engagement with the pulley 34 and, conversely, when the rod 54 is pushed back, the clutch is thrown in and causes the hopper 6 to be rotated. With this construction, the hopper 6 may be operated while the other parts of the machine are at rest in order to obtain an abundant supply of nails in the raceway.

Screwed to the outer bar 23 of the raceway 8 within the hopper 6 is a vertical plate 58 having its right-hand face (Fig. 10) spaced from the center line of the slot of the raceway 8 by a distance slightly greater than half of the largest transverse dimension of the heads of the nails on which the machine is designed to operate. The upper edge of the

inner bar 24 of the raceway is chamfered off on its inner side as indicated at 60 so that it extends from the center line of the slot of the raceway by a distance less than half 5 the width of the heads of the nails. The upper end of the raceway 8 and the flanges 7 of the hopper 6 are so arranged with relation to each other that the major portion of the nails lifted from the hopper by the flanges 10 are delivered against the inner face of the wall 58 or fall directly on the upper edge of the raceway. If nails having large heads were allowed to collect on the upper end of the raceway, their heads would be likely to 15 interlock, thereby causing them to clog the raceway. In such an event, the collected nails not only would not themselves enter the slot of the raceway but would also prevent other nails from doing so. If a nail 20 is delivered on to the raceway 8 with its shank extending from the edge of the raceway so as not readily to enter the slot of the raceway, it will fall quickly from the raceway by reason of the narrow support provided for it by the raceway bars 23 and 24. Consequently, nails are prevented from collecting on the raceway in sufficient numbers 25 to clog it. Nevertheless, by the use of the illustrated construction, the raceway may be 30 kept adequately supplied with nails.

In order to remove from the raceway nails whose shanks have not properly entered the raceway slot, I provide a knock-off device 35 slidably supported on the cover 64 of the raceway and comprising a bar 66 having an enlarged portion 68 at its rear end to which is attached a knock-off plate 70. The cover 64 may be clamped to the plate 12 in various 40 positions of vertical adjustment by bolts 71 passing through vertically elongated slots in the cover. Movement is imparted to the bar 66 by an arm 72 carrying a stud fitting into a recess 74 in the bar. The recess 74 permits the cover 64 to be adjusted vertically without 45 affecting the operative connection between the bar 66 and arm 72. The arm 72 is clamped on the forward end of a shaft 76 journaled in bearings 78 and 80 in the frame member 10, and fast on the rear end of the 50 shaft is a bell-crank lever 82 having one of its arms 84 extending into the path of movement of wipers 85 on the hub of the gear 29. The other arm 86 of the lever 82 has its end disposed to abut against an adjustable stop screw 88 threaded into the frame member 10 and is normally maintained in engagement 55 with the screw 88 by a coil spring 90 (Fig. 2). The bar 66 is moved positively toward the delivery end of the raceway by the wipers 85 and is snapped back by the spring 90 to an extent determined by the position of adjustment of the stop screw 88.

The cover 64 is formed on its under side with a rearwardly extending projection 92 60 which is fitted into the enlarged portion 68

of the bar 66 and co-acts with it to define a space above the raceway of a shape and size corresponding substantially to the shape and size of the heads of the nails to be inserted by the machine, the upper and central portion of 70 the space being provided mainly by the projection 92 and the sides of the space being bounded by the portion 68. The plate 70 is cut away from its lower edge to accord with the portion 68 and is formed with prongs 94 75 extending rearwardly from its lower edge and overlying the upper edges of the bars 23 and 24 of the raceway. The space between the prongs 94 is preferably only slightly wider than the heads of the nails being operated upon in order that the points of nails 80 may not enter between the prongs and the head of the nail beneath the plate 70. In the absence of preventive means, a nail on the raceway might repose with its head against 85 the stationary end of the projection 92 of the cover 64 out of the field of action of the knock-off device and thus impede the movement of the nails down the raceway. To prevent this, the plate 70 is provided with a 90 lug 96 arranged to travel upon reciprocation of the knock-off bar 66 in an open-ended slot 98 in the projection 92. The plate 70 is rabbeted on the end of the bar 66 and is detachably secured to the bar 66 by a bolt 102. 95 Consequently, if desired, the plate 70 may be removed and another plate of a form better suited to the particular lot of nails being inserted substituted for it.

The nails are delivered singly from the raceway 8 to a nail receiver 104 mounted for to and fro movement on the superstructure 4 between the raceway and the line of drive of the nails. As shown, the nail receiver is formed with a laterally projecting wing 105 100 screwed to the lower end of a head 106 supported for swinging movement on the front of the superstructure 4 about the shaft 40 and secured in place on the superstructure 4 by clamps 108 in a manner which will be 105 clearly understood by those skilled in the art. The nails are forced into the work by a driver 109 reciprocable vertically in a combined driver and nail passage in the receiver. The driver bar 110 is mounted for reciprocation 110 in the head 106, being elevated by a lifting cam 112 on the shaft 40 and a block 114 on the driver bar to allow a nail to be introduced into the receiver 104 below the driver and being depressed by a spring operated arm 116 115 and link 118 to drive the nail. Since the illustrated devices for effecting driving movement of the driver bar are well known in the art, a more complete description of them is deemed unnecessary. 120

The nail receiver 104 comprises a throat member 120 (Fig. 7) formed to provide a chamber open on the side toward the raceway 8 to enable nails to be successively introduced into the throat and a pair of guides 122 130

- into which nails drop from the throat. The guides 122 are chambered at 123 to provide a passage between them of a size to receive freely the heads of the nails to be driven.
- 5 Above the passage 123, the guides are beveled upwardly and outwardly as indicated at 124 to avoid all possibility of the head of a nail delivered to the throat coming into supporting engagement with the up-
10 per surface of either of the guides. Below the passage 123 each of the guides 122 flares inwardly at 126 to a semi-circular notch 128, the notches 128 in the normal positions of the guides affording a circular opening
15 large enough to receive the shanks of the nails but too small to permit the heads of the nails to pass through it. The guides 122 are pivoted to the throat member 120 on pins 130 and are normally held together by springs 132.
- 20 In order to prevent the nails from turning in the throat as they are driven, the outward movement of each of the guides 122 is arrested by a stop 136 on the throat member after the guide has been moved through a distance
25 slightly greater than half the width of the heads of the nails being inserted. Inasmuch as the points of the nails are centered in the opening formed by the notches 128 and the nails can pass from the throat only by effecting substantially equal movements of the guides, they are, perforce, driven straight into the work.
- The improper escape of nails from the delivery end of the raceway 8 is prevented by
30 a retainer 138 pivoted on the cover 64 of the raceway and pressed downwardly by a spring 139. In the operation of the machine, the throat 120 is moved toward the raceway to a point such as to enclose the endmost nail in the raceway. To permit such movement, the throat is recessed at 140 and 141 to receive the points of the raceway and the retainer 138 respectively. In order to isolate the endmost nail in the raceway from the remaining nails
40 and to cause it to be presented to the line of drive of the nails upon reverse movement of the nail receiver 104, I utilize a separator 142 movable with the swinging head 106. Preferably, and as shown, the separator comprises
45 a shank engaging portion 144 recessed at 145 and a head engaging portion 146. The separator is fixed by a screw or the like to a lever 148 (Fig. 4) fulcrumed on a stud 150 on the head 106 and is moved away from the line of
50 nails in the raceway by a cam 154 on the shaft 40, rotating in the direction indicated by the arrow (Fig. 4). The separator is caused to enter between the endmost nail in the raceway and the next adjacent nail under
55 the control of the cam 154 by a spring 156. The path of the cam 154 is formed with a low portion 158, an intermediate portion 160, and a high portion 162 for a purpose which will appear hereinafter.
- 60 The work is supported in the use of the ma-

chine on a horn 164 (Fig. 1) arranged to be periodically depressed, to enable the work to be fed, by mechanism including a rod 165 operated by a cam 166 on the shaft 40. In order to guide the work as it is fed and to 70 position it with reference to the fastening inserting mechanism, the machine is also equipped with an edge gage 167 of suitable design.

75 Preferably, and in the illustrated construction, the work is fed by an awl 168 carried by an awl bar 170 slidable vertically in a guideway in an awl bar carrier 172 fulcrumed on a shaft 174 journaled in bearings 176 and 178 on the superstructure 4 of the machine. Vertical movements of the awl to cause it to penetrate the work and to be withdrawn from the work are effected by a link 180 connected at one end to the awl bar 170 and at its other end to an arm 182 having its hub 184 clamped on to the shaft 174. The shaft 174 is in turn operated by an arm 186 fast on the shaft and carrying a roll riding in a groove in a cam 188 on the shaft 40.

80 The awl carrier 172 is operated in a plane parallel to the plane of movement of the head 106 to move the awl 168 into the line of drive of the nails to feed the work and to retract it from the line of drive. As shown, the 85 movements of the swinging head 106 to traverse the nail receiver 104 between the raceway 8 and the line of drive of the nails and of the awl carrier 172 into and away from the line of drive of the nails are effected by 90 mechanism including a common actuating arm 190 depending from a shaft 192 journaled in bearings 194 and 196 on the superstructure 4 and operated by an arm 198 having a roll riding in a groove in the cam 188. The arm 190 on its forward side is formed 95 with a T-shaped groove 200 in which is slantly mounted the similarly shaped head of a sleeved block 202 threaded to receive a bolt 204 which may be turned against the inner surface of the groove 200 to clamp the block 202 against the inturned portions 206 of the arm 190 and thereby secure the block in any desired position of adjustment in the groove 200. Fitted over the block 202 within a slot 100 208 in the awl bar carrier 172 are recessed blocks 210 and 212 adapted to slide in the groove 208. To the end that any looseness 105 due to wear or other cause between the blocks 210 and 212 and the walls of the slot 208 may be taken up, the outer wall of the slot is constituted by a triangular piece 214 (Fig. 2) dovetailed into the main body of the awl carrier and fixed thereto by a bolt 216 passing through a slot (not shown) in the piece. The connections between the arm 190 and the 110 swinging head 106 are similar to those between it and the awl carrier 172, comprising a block 218 mounted for sliding adjustment in a T-shaped groove 220 in the arm 190, a threaded bolt 222 for clamping the block 218 115

120

125

130

in adjusted position in the groove 220, and recessed blocks 224 and 226 fitted on the block 218 within a slot 228 in the swinging head. The outer wall of the slot 228 is formed by 5 a piece 230 dovetailed into the head and secured thereto by a screw bolt 232 passing through a slot 234 in the piece so that any excessive looseness which may arise between the blocks 224 and 226 and the walls of the 10 slot 228 may be eliminated. Manifestly, the range of movement of the swinging head 106 may be increased or decreased, as desired, by depressing or elevating the block 218 in the slot 228 and groove 220. It is contemplated, 15 however, that adjustment of the block 218 will not be often necessary, after it has once been properly located in the setting up of the machine.

The arm 190 and its groove 200 and the 20 awl bar carrier 172, pivot shaft 174, and slot 208 are so arranged that when the arm 190 has been swung to the limit of its movement to the left (Fig. 12) to carry the awl 168 into the line of drive of the nails, the groove 200 and slot 208 are both vertically disposed. Consequently, the awl 168 will always be properly registered with the line of drive of the 25 nails at the termination of its feeding movement regardless of the position of adjustment 20 of the block 202 in the groove 200. The centers of oscillation of the arm 190 and awl bar carrier 172, however, are so disposed that when the arm 190 has been swung to the right (Fig. 2), the groove 200 of the arm is positioned at a considerable angle to a vertical 30 plane through the axis of the block 202 on one side of the plane, whereas the slot 208 is positioned at a slight angle to the plane on its opposite side. With this construction and 35 arrangement of parts, as clearly appears from Fig. 2, the extent of movement of the awl 168 from the line of drive of the nails may be appreciably increased or decreased, as desired, by adjusting the block 202 downwardly or upwardly in the groove 200. It will be 40 noted further that, inasmuch as the connections between the arm 190 and the swinging head 106 do not include the block 202, the amount of work feeding movement of the awl 45 may be varied without affecting the range of movement of the head 106.

The machine is provided with clutch mechanism 236 of a well-known type and designed to stop the machine always at a certain point 50 in its cycle.

The manner of operation of the illustrated machine will now be described. The machine is stopped just subsequent to the driving of a nail, the parts being then in the relative positions seen in Fig. 2. The throat 120 and driver 109 are, of course, in driving position and the driver is down. The awl 168 is up and at the limit of its movement to the right. The separator 142 is in far enough to register 55 the recess 145 with the open side of the

throat so that the separator constitutes a wall across the open side of the throat and in position to prevent the escape of nails from the throat. The horn 164 is up. Upon the initiation of the operation of the machine, the 70 high part 162 of the cam 154 is brought into engagement with the roll on the upper end of the lever 148, thus causing the separator 142 to be fully retracted so as to expose the open side of the throat. Meantime, the awl 168 is 75 depressed to penetrate the work, the awl completing its downward movement just subsequent to the completion of the retracting movement of the separator. The driver is raised at about the time that the awl completes its downward work penetrating movement. The horn 164 is moved down as the driver rises, after which the head 106, carrying the nail receiver 104, and the awl carrier 172 are moved to the left in substantially constant relation. Upon the completion of the movement of the swinging head 106 and the awl carrier 172 to the left, the horn 164 is moved up, and, when it has substantially completed its upward movement, the awl 168 80 begins to rise. At the same time, the roll on the separator lever 148 comes into engagement with the depressed portion 158 of the cam 154, thus causing the separator to be projected between the endmost nail in the raceway and the remaining nails. The separator 85 completes its inward movement across the line of nails in the raceway about the time that the awl 168 is fully raised. The throat 120 and awl 168 are then moved to the right 90 together with the separator 142. The roll on the separator lever 148 engages the dwell or intermediate portion 160 of the cam 154 at about the time that the nail is freed from the raceway, thus alining the recess 145 of the 95 portion 144 of the separator with the nail and, in effect, withdrawing the separator from the nail so as to facilitate the discharge of the nail to the throat. The driver is then depressed to drive the nail. 100

A machine constructed as hereinbefore described will operate efficiently on nails of widely varying forms both with respect to their heads and shanks. It is particularly well adapted, however, for operation on nails having heads substantially circular in transverse section (that is, in section taken at right angles to the axis of the shank of the nail), such as the various species of "Hungarian" 115 nails.

In order better to adapt the machine to insert nails of certain special forms, some or all of the parts illustrated in Figs. 13 to 17 inclusive may be substituted for corresponding parts of the machine as hereinbefore described. For example, when it is desired to insert hob-nails having square heads, a separator 142' of the form shown in Fig. 16 is 120 preferably employed. Such nails are usually very irregular in shape and non-uniform as to 125

size. The heads of such nails are also frequently fluted as shown in Fig. 17. The shanks of hob nails are also usually rectangular in section including the portions adjacent 5 to the nail heads which are received in the slot of the raceway. It is very difficult to isolate such nails and to deliver them from the raceway into proper driving position. When a separator is employed which engages 10 the heads of the nails, it is likely not to pass through between the head of the endmost nail in the raceway and the next adjacent nail, but to engage a projecting angle on the head of the nail and tend to turn the nail. By 15 reason of the shape of the nail shank, such turning movement causes the nail to cramp in the raceway so that it cannot be moved from it. For these reasons, the separator 142' is constructed to engage the shank only of a nail. 20 Preferably, also the separator 142' comprises a thin plate provided with a flange 236 projecting from its upper edge in the direction of the line of drive of the nails and is recessed somewhat at 238 beyond the end of the flange. 25 Flange 236 extends along the upper edge of the separator 142' toward its entering end, but terminates short of its entering end (as shown in Fig. 16) by a distance at least as great as or somewhat greater than the diameter 30 or width of the heads of the nails which the machine is to insert. The extent of projection of the flange 236 from the separator 142' is slightly greater than the amount of overhang of the heads of the nails from their 35 shanks so as to compensate for the overhang of the heads of the nails and facilitate their discharge from the separator at the recess 238.

Preferably, also, when it is desired to insert hob-nails of the character above described, a 40 nail receiver 104' constructed as shown in Fig. 13 is substituted for the nail receiver 104. The nail receiver 104' is similar to the receiver 104 except in the respects noted below. Pivoted to the nail receiver 104' by pins 239 45 are combined throat and guide members 240 normally pressed toward each other by leaf springs 242. With this construction, the throat as well as the guides below is allowed to expand, which action is useful in case of 50 the delivery to the nail receiver of a nail having an excessively large head. It is desirable, therefore, when the machine is used for inserting nails having heads of varying sizes to equip it with a nail receiver of the form designated 104'. The nail receiver 104' is notched at 244 to receive the nail retainer, and the members 240 are cut away at 246 to receive the ends of the raceway 8. As shown, 55 each of the members 240 has a projection 248 on its lower end extending toward the raceway, and upstanding from the projections 248 are lugs 250 spaced from the main bodies of the members 240 and co-acting therewith to constitute positive controlling and guiding 60 means for the separator 142'. The lugs 250

support the separator 142' against movement away from the nail receiver 104' in the vertical plane of the raceway 8. The flange 236 of the separator 142' fits into a channel 252 in the rear member 240, and the front member 70 240 is notched at 254 to receive the flange 236 when the separator 142' approaches the forward limit of its movement.

When the nails are delivered to the nail receiver 104' by a separator arranged for engagement with the shanks only of the nails, the raceway 8 and its cover should be constructed to control the heads of the nails in such a manner as to preclude them from turning about their heads, inasmuch as, in such 80 an event, the nails probably would not be delivered to the nail receiver so as to enable them to be properly driven. In order so to control the heads of the nails and also to retain control of the nails until they arrive substantially at the line of drive, the cover 64 and retainer 138 may be replaced by corresponding parts 64' and 138' of greater projection from the raceway 8 than the parts 64 and 138. As shown, the nail receiver 104' is cut away 90 at 256 to receive the end of the cover 64' when the receiver is moved toward the raceway 8, and the cover is forked at its end to receive the retainer 138' and the driver which passes just to the right of the retainer (Fig. 17). If 95 need arises, the plates 26 may be detached from the bars 23 and 24 of the raceway 8 and other plates substituted therefor in order better to adapt the machine for operation on nails of the specific character which it is desired 100 to insert.

Having fully described my invention, what I claim as new and desire to secure by Letters Patent is:—

1. In a machine of the class described, a 105 frame, a head mounted for to and fro movement on the frame, a fastening receiver carried by the head for movement between fastening receiving position and a position in the line of drive of the fastenings, mechanism for operating the head, means for supplying fastenings to the receiver, means for driving the fastenings, an awl, a carrier for the awl mounted on the frame for movement independently of the 110 head, and means for operating the awl carrier. 115

2. In a machine of the class described, a 120 frame, a head mounted for to and fro movement on the frame, fastening inserting mechanism carried by the head, an awl for feeding the work past the fastening inserting mechanism, a carrier for the awl mounted on the frame for movement independently of the head, and means for operating the head and 125 the awl carrier.

3. In a machine of the class described, a 130 frame, a head mounted for to and fro movement on the frame, fastening inserting mechanism on the head including a driver, means

for delivering fastenings to the fastening inserting mechanism, an awl for feeding the work relatively to the fastening inserting mechanism, an awl carrier mounted on the frame and movable independently of the head to carry the awl into and out of the line of drive, means for operating the awl carrier, and means for moving the head from the line of drive of the fastenings into and out of operative relation to the delivering means, in a plane substantially parallel to the direction of movement of the awl carrier.

4. In a machine of the class described, a frame, a head mounted for swinging movement on the frame and carrying a throat and a driver, means for supplying fastenings to the throat comprising a raceway, means for operating the head to traverse the throat between the delivery end of the raceway and the line of drive of the fastenings, an awl for feeding the work past the fastening inserting mechanism, an awl carrier mounted on the machine frame for movement independently of the swinging head, and means for operating the awl carrier to move the awl into and out of the line of drive of the fastenings.

5. In a machine of the class described, a frame, a head mounted for swinging movement on the frame and carrying a throat and a driver, means for supplying fastenings to the throat comprising a raceway, means for operating the head to traverse the throat between the delivery end of the raceway and the line of drive of the fastenings, an awl for feeding the work past the fastening inserting mechanism, an awl carrier mounted on the machine frame for movement independently of the head, and means including a common actuator for operating the head and the awl carrier.

6. In a machine of the class described, a frame, a head mounted for swinging movement on the frame and carrying a throat and a driver, means for supplying fastenings to the throat comprising a raceway, means for operating the head to traverse the throat between the delivery end of the raceway and the line of drive of the fastenings, an awl for feeding the work past the fastening inserting mechanism, an awl carrier mounted on the machine frame for movement independently of the head, an arm interposed between the awl carrier and the head, and means associated with said arm for operating both the awl carrier and the head.

7. In a machine of the class described, a frame, a head mounted for swinging movement on the frame and carrying a throat and a driver, means for supplying fastenings to the throat comprising a raceway, means for operating the head to traverse the throat between the delivery end of the raceway and the line of drive of the fastenings, an awl for feeding the work past the fastening inserting mechanism, an awl carrier fulcrumed on the

machine frame for movement independently of the head and provided with a slot, means for operating the awl carrier comprising an arm provided with a channel adjacent to the slot of the awl carrier, and means movable in the slot of the awl carrier and the channel of the arm for operatively connecting the arm and the awl carrier, the arm and the awl carrier being so constructed and arranged that the slot of the awl carrier and channel of the arm are substantially aligned with each other when the awl is disposed in the line of drive of the fastenings so that the range of movement of the awl and, consequently, the extent of feed of the work between successive fastening insertions may be varied without affecting the presentation of the opening made in the work by the awl to the line of drive of the fastenings.

8. In a machine of the class described, a frame, a head mounted for to and fro movement on the frame, fastening inserting mechanism carried by the head, means for delivering fastenings to the fastening inserting mechanism, means for operating the head to traverse the fastening inserting mechanism between the line of drive of the fastenings and the delivering means, an awl, and means separate from the head for moving the awl in a direction substantially parallel to the direction of to and fro movement of the head to cause the awl to feed the work.

9. In a machine of the class described, a frame, a swinging head mounted on the frame, nail inserting mechanism including a driver carried by the head, a nail hopper, means for delivering loose nails from the hopper to the nail inserting mechanism, an awl, mechanism for swinging the head to traverse the nail inserting mechanism between the line of drive of the fastenings and the delivering means and for operating the awl in a direction substantially parallel to the direction of movement of the head to feed the work, means for operating the awl in a path substantially perpendicular to the axis of swinging movement of the head to cause the awl to pierce and withdraw from the work, means for operating the driver in a path substantially perpendicular to the axis of swinging movement to drive nails in the holes formed by the awl, and means for varying the feed of the work by the awl without changing the extent of to and fro movement of the head.

10. In a machine of the class described, a swinging head mounted for to and fro movement about a horizontal axis, fastening inserting mechanism carried by the head, means for delivering loose fastenings from bulk to the fastening inserting mechanism, an awl, means for operating the head to traverse the fastening inserting mechanism between the line of drive of the fastenings and the delivering means and for operating the awl in a direction substantially parallel to the direction

of movement of the head to feed the work, means for operating the awl in a path substantially perpendicular to the axis of swinging movement of the head, and mechanism 5 for varying the feed of the work by the awl without affecting the extent of to and fro movement of the head or the line of drive of the fastenings, said mechanism and said operating means being constructed and arranged 10 to cause the feeding movement of the awl to terminate in the line of drive of the fastenings in all positions of adjustment of the mechanism.

11. In a machine of the class described, a 15 frame, a horizontal shaft journaled in the frame, a head mounted on the shaft for swinging movement, fastening inserting mechanism carried by the head including a driver movable in a path substantially at 20 right angles to said shaft, a hopper for loose fastenings, means for delivering loose fastenings from the hopper to the fastening inserting mechanism, work feeding means, mechanism for operating the head to traverse the 25 fastening inserting mechanism between the line of drive of the fastenings and the delivering means and for operating the work feeding means, and means for varying the feed of the work without changing the extent of 30 the to and fro movement of the head.

12. In a machine of the class described, a raceway for conducting fastenings, mechanism including a receiver for the fastenings operable relatively to the raceway into position to enclose the endmost fastening in the raceway and to move during movement of the fastening to the line of drive of the fastenings, and means for driving the fastenings.

13. In a machine of the class described, a 40 raceway for conducting fastenings, fastening inserting mechanism, means co-operating with the fastening inserting mechanism to isolate the endmost fastening in the raceway from the remaining fastenings, and means for 45 operating fastening inserting mechanism and the isolating means in substantially the same direction to withdraw the endmost fastening from the raceway and move it to the line of drive of the fastenings.

50 14. In a machine of the class described, a raceway for conducting fastenings, fastening inserting mechanism comprising a fastening receiver and a driver, a separator for isolating a fastening in the raceway from the remaining fastenings, and means for operating the receiver and separator substantially in the same direction to move the fastenings successively away from the raceway to the line of drive of the fastenings.

60 15. In a machine of the class described, a raceway, a driver, means for delivering fastenings from the raceway and presenting them to the driver, comprising a fastening receiver movable to enclose the endmost fastening in the raceway, and a separator oper-

able to isolate the endmost fastening from the remaining fastenings while it is enclosed by the receiver.

16. In a machine of the class described, a raceway, a driver, and means for delivering 70 a fastening from the raceway and presenting it to the driver, comprising a fastening receiver constructed to provide a chamber open at one side to enable a fastening to enter the receiver and movable to a position to enclose 75 the endmost fastening in the raceway and a separator movable across the open side of the receiver rearwardly of the fastening to form with the receiver a substantially closed chamber about the fastening until it is driven. 80

17. In a machine of the class described, a raceway, a fastening receiver and a separator constructed to form a substantially closed chamber about the endmost fastening in the raceway, means for operating said parts to 85 cause the fastening to be withdrawn from the raceway to the line of drive of the fastenings, and means for driving the fastenings.

18. In a machine of the class described, a raceway, a fastening receiver and a separator 90 constructed to form a substantially closed chamber about the endmost fastening in the raceway, a retainer disposed for engagement with the endmost fastening in the raceway, means for operating the receiver 95 and separator together to withdraw the fastening from the raceway, said retainer being yieldably mounted to enable the fastening to be withdrawn but operable to prevent the escape of other fastenings from the raceway, 100 and means for driving the fastenings.

19. In a machine of the class described, a raceway, a retainer disposed for engagement with the endmost fastening in the raceway, a separator operable to isolate the endmost 105 fastening from the remaining fastenings by thrusting the fastening adjacent to the endmost fastening away from the endmost fastening while the last-mentioned fastening is maintained in position by the retainer, means 110 for moving the separator in a direction substantially parallel to the length of the raceway to remove the endmost fastening from the raceway, and means for driving the fastenings. 115

20. In a machine of the class described, a raceway, a cover for the raceway arranged to prevent escape of fastenings upwardly from the slot of the raceway, a retainer mounted on the cover and disposed for engagement with the endmost fastening in the raceway, a fastening receiver, a separator operable to isolate the endmost fastening from the remaining fastenings in the raceway by thrusting the fastening adjacent to 120 the endmost fastening away from the endmost fastening while the last-mentioned fastening is maintained in position by the retainer and co-acting with the receiver to form 125 a substantially closed chamber about the end- 130

- most fastening, means for moving the receiver and separator in substantially the same direction to withdraw the fastening from the raceway and move it to the line of drive 5 of the fastenings, and means for driving the fastenings.
21. In a machine of the class described, fastening inserting mechanism, means for delivering fastenings singly to the fastening inserting mechanism comprising a separator in the form of a thin plate having a flange extending towards its end to engage the shank of the nail to be separated, said flange terminating short of the end of the separator 10 by a distance at least as great as the diameter of the heads of the nails to be inserted, and means for operating the separator in opposite directions, said separator being operable upon movement in one direction to isolate a fastening from adjacent fastenings in the delivering means and in the opposite direction to permit the passage of another fastening past the separator.
22. In a machine of the class described, a raceway, a separator arranged for engagement with the shanks of fastenings in the raceway and formed with a reduced portion adjacent to its leading end, and operating means for the separator constructed to advance the separator to carry the reduced portion across the line of the fastenings in the raceway and to isolate the endmost fastening from the remaining fastenings, said operating means being further constructed to cause 35 a dwell in the reverse movement of the separator when the reduced portion of the separator has been moved into the line of the fastenings in order to facilitate the delivery of the fastenings from the raceway by avoiding interference by the separator with the heads of the fastenings.
23. In a machine of the class described, a fastening receiver, a raceway, a separator arranged for engagement with the shanks of the fastenings in the raceway and formed with a reduced portion adjacent to its leading end, means for moving the receiver and separator together in a direction substantially parallel to the line of fastenings in the raceway to remove a fastening from the raceway, and operating means for the separator constructed to advance the separator to carry the reduced portion of the separator across the line of fastenings in the raceway and to isolate the endmost fastening from the remaining fastenings previous to the movement of the separator and the receiver to withdraw the fastening from the raceway, said operating means being constructed to cause a dwell in the reverse movement of the separator when the reduced portion of the separator has been brought into line with the fastening in the raceway thereby facilitating the delivery of the fastenings from the raceway.
24. In a machine of the class described, a fastening receiver constructed to provide a chamber open at one side, a raceway, means for operating the fastening receiver to enclose the endmost fastening in the raceway, a separator adapted to enter between the endmost fastening in the raceway and the next adjacent fastening to isolate the endmost fastening from the remaining fastenings and coacting with the fastening receiver to constitute a substantially closed chamber about the fastening, said separator being arranged for engagement with the shank of a fastening and being provided with a recess adjacent to its leading end, means for moving the fastening receiver and separator together to withdraw the fastening from the raceway, and means for advancing the separator along the open side of the fastening receiver previous to the withdrawal of a fastening by the separator and the receiver to isolate the endmost fastening and for moving the separator reversely to expose the open side of the fastening receiver to enable the receiver to enclose another fastening in the raceway, said last-named means being constructed to cause the separator to dwell in its reverse movement with the recess in register with the fastening to facilitate the delivery of the fastening from the raceway.
25. In a machine of the class described, a driver, and mechanism including a reciprocating separator formed with a flange terminating a substantial distance short of the end of the separator, said flange being positioned to underlie the head of a nail being separated and constructed and arranged successively to present nails having heads of angular transverse section to the driver in proper position to be inserted by the driver.
26. A separator for fastening inserting machines formed and arranged to be inserted between the endmost and the adjacent nail in a raceway, and comprising a plate having a thin entering end and a flange extending toward but terminating a substantial distance short of said entering end and positioned to underlie the head of a nail as it is separated.
27. A separator for fastening inserting machines formed and arranged to be inserted between the nail to be separated and the adjacent nail in a raceway and comprising a shank engaging plate and a flange, the plate having a thin entering end toward which the flange extends, said flange being positioned to underlie the head of a nail as it is separated and terminating at a distance from said entering end equal to or greater than the width of the heads of the mails with which the separator is to be used, and said plate having a recess near its entering end and beyond the ends of the flange.
28. In a machine of the class described, a driver, a raceway, a nail receiver mounted

for movement from the line of drive of the nails toward the raceway and back to the line of drive, means for delivering a nail from the raceway to the receiver upon movement 5 of the receiver toward the line of drive, and means associated with the raceway for retaining control of the nail until it is moved substantially to the line of drive.

29. In a machine of the class described, a 10 fastening receiver, a raceway, a separator adapted to enter between the endmost fastening in the raceway and the next adjacent fastening to isolate the endmost fastening from the remaining fastenings, said separator having 15 a portion spaced from its entering end and projecting from the separator in the direction of its movement in withdrawing a fastening from the raceway and a reduced portion, means for moving the receiver and 20 separator together to withdraw a fastening from the raceway, and operating means for the separator constructed to advance it to dispose the projecting part of the separator in engagement with the shank of a fastening 25 prior to the withdrawal of the fastening from the raceway, to effect reverse movement of the separator at the end of the common movement of the separator and receiver to register the reduced portion of the separator 30 with the fastening to facilitate the delivery of the fastening to the receiver and also to prevent escape of a fastening from the receiver, and then to impart a further reverse movement to the separator to permit another 35 fastening to enter the receiver.

30. In a machine of the class described, a nail receiver, a raceway, a separator adapted to enter between the endmost nail in the raceway and the next adjacent nail to isolate the 40 endmost nail from the remaining nails, said separator having a portion enlarged in the direction of movement of the separator in withdrawing a nail from the raceway and a reduced portion, means for moving the 45 separator in a direction substantially parallel to the line of nails in the raceway to deliver the endmost nail from the raceway to the receiver, and means for advancing the separator prior to the removal of the nail from the 50 raceway to register the enlarged portion of the separator with the shank of the nail and for effecting reverse movement of the separator upon the delivery of the nail from the raceway to register the reduced portion of the 55 separator with the nail, said enlarged portion being constructed to compensate for the overhang of the heads of the nails and thus to facilitate the delivery of the nails from the raceway.

60 31. In a machine of the class described, a fastening receiver, a raceway, a separator adapted to enter between the endmost fastening in the raceway and the next adjacent fastening to isolate the endmost fastening from 65 the remaining fastenings, said separator hav-

ing a flange extending therefrom in the direction in which the separator moves in withdrawing a nail from the raceway and to an extent to cause it to compensate for the overhang of the heads of the fastenings and a reduced portion between the flange and the entering end of the separator, means for moving the receiver and separator together away from the raceway in a direction substantially parallel to the line of the fastenings in the 70 raceway to withdraw the fastenings successively from the raceway, and means for advancing the separator prior to the removal of a fastening from the raceway to register the flange of the separator with the shank 75 of the fastening and for effecting reverse movement of the separator upon the delivery of the fastening from the raceway to register the reduced portion of the separator with the fastening, so as to facilitate the delivery of 80 the fastenings from the raceway by the separator and also to prevent the escape of fastenings from the fastening receiver while they are being driven, and means for driving 85 the fastenings. 90

32. In a machine of the class described, a raceway, a separator for isolating the endmost fastening in the raceway and delivering it from the raceway, a fastening receiver mounted for to and fro movement between the raceway and the line of drive of the fastenings and constructed and arranged to control the separator, means for operating the fastening receiver, and means for driving the fastenings. 95

33. In a machine of the class described, a raceway, a separator for isolating the endmost fastening in the raceway and delivering it from the raceway, a fastening receiver mounted for to and fro movement between 100 the raceway and the line of drive of the fastenings and constructed and arranged to guide the separator and maintain it against lateral movement, means for operating the fastening receiver, and means for driving 105 the fastenings. 110

34. In a machine of the class described, a raceway, a separator for isolating the endmost fastening in the raceway and delivering it from the raceway, a fastening receiver 115 mounted for to and fro movement between the raceway and the line of drive of the fastenings and comprising guides normally providing a passage between them of less dimensions than the heads of the fastenings, means for supporting the guides for movement away from each other to enable a fastening to pass between them, means carried by the guides for maintaining the separator in proper relation to the fastening receiver, and means 120 for driving the fastenings. 125

35. In a machine of the class described, a raceway, a separator for isolating the endmost fastening in the raceway and delivering it from the raceway, a fastening receiver 130 .

- mounted for to and fro movement between the raceway and the line of drive of the fastenings and comprising a pair of guides normally providing a passage between them of 5 less dimensions than the heads of the fastenings, means for supporting the guides for movement away from each other to enable a fastening to pass between them, lugs on the guides spaced from the bodies of the guides 10 and acting to guide the separator and to maintain it in proper relation to the fastening receiver, and means for driving the fastenings.
36. In a machine of the class described, a 15 raceway, a fastening receiver formed to provide a chamber open on one side, said receiver being cut away at the open side of the chamber, means for moving the receiver between the delivery end of the raceway and the line 20 of drive of the fastenings, a cover on the raceway having its end extended to the line of drive in the direction of movement of the fastenings from the raceway and adapted to enter the cut away portion of the receiver 25 upon movement of the receiver toward the delivery end of the raceway, a separator for delivering fastenings singly from the raceway to the receiver, and a driver for the fastenings.
37. In a machine of the class described, a 30 raceway, a fastening receiver and a separator movable in the same direction to withdraw a fastening from the raceway and to move it to the line of drive of the fastenings, a 35 cover for the raceway acting to prevent the escape of fastenings upwardly from the raceway and constructed to control the fastenings during their entire movement to the line of drive, and means for driving the fastenings.
38. A fastening inserting machine having, 40 in combination, a stationary raceway, a swinging head, fastening inserting means carried by the swinging head, and a separator also carried by the swinging head and 45 arranged for movement between the endmost fastening in the raceway and the fastening adjacent thereto when the head has been swung towards the raceway so as to move the endmost fastening from the raceway when 50 the head is swung in the opposite direction.
39. A fastening inserting machine having, 55 in combination, a stationary raceway, a head mounted for to and fro movement towards and from the raceway, and a separator mounted upon the head for nail separating movement transversely of the raceway and movable with the swinging head in the general direction of the length of the raceway to transfer nails from the end of the raceway to 60 fastening inserting position.
40. A fastening inserting machine having, 65 in combination, a stationary raceway and a separator constructed and arranged for separating movement transversely of the raceway, a throat, and means for moving the throat and the separator in the general direction of the length of the raceway to transfer nails away from the raceway to nail inserting position.
41. A fastening inserting machine having, 70 in combination, a raceway, a throat, and a separator arranged to transfer fastenings from the raceway to the throat, the separator and the throat being mounted for movement 75 relative to the raceway in the general direction of the length of the raceway.
42. A fastening inserting machine having, 80 in combination, a raceway and a throat arranged to receive fastenings therefrom, the raceway and throat being arranged for relative movement in the general direction of the length of the raceway into and out of juxtaposition to facilitate the transfer of fastenings from the end of the raceway to inserting position in the opening of the throat.
- In testimony whereof I have signed my name to this specification.

GEORGE GODDU.
